(57) CLAIM

The ornamental design for a removable inner bag for a handbag, as shown and described.

DESCRIPTION

FIG. 1 is a front, side perspective view of the removable inner bag for a hand bag shown broken away in the middle to indicate indeterminate length;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken line showing of a hand bag is for illustrative purposes only and forms no part of the claimed design.
